UNITED STATES PATENT OFFICE.

JOHN K. CASSEL, OF AINSWORTH, NEBRASKA.

FILING ENVELOPE.

Application filed September 20, 1923. Serial No. 663,898.

The object of this invention is to provide a bandless filing envelope including particular means for rendering the device adjustable, so that it will fit and secure the packet 5 of papers to be inclosed therein.

A further object is to provide in a device of this type, a main or back portion of heavy paper or tag board, means secured thereto for reinforcing the back and retaining the 10 ends of the papers to be filed, and particular securing means described below.

A still further object is to provide one edge of the back with a flat resilient element, and to provide the long edges of the 15 back with a series of pockets or the like adapted to receive the ends of the resilient element when the latter is flexed and then allowed to resume its normal flat position, thereby closing the envelope and securing it 20 without the necessity of providing bands or other similar devices.

With the foregoing and other objects in view, the invention consists in the novel construction and arrangement of elements described, illustrated, and claimed, it being understood that modifications may be made within the scope of the claim, without departing from the spirit of the invention.

In the drawings, Figure 1 is a plan view 20 of the envelope, unfolded; Figure 2 is a transverse section through the folded envelope; Figure 3 is a longitudinal section; Figure 4 is a longitudinal section through the element at the left of Figure 1; Figure 35 5 is a fragmentary section of a part of the structure at the right of Figure 1; Figure 6 is a section through one of the reinforced pockets and edge portions.

The sheet of heavy paper or tag board of 40 which the device is formed includes a rectangular portion 10 which will be termed the front, an adjacent rectangular portion 11 having score lines 12 and a folded over portion 13. The latter is cut away at 14, 45 15, and incloses a securing device comprising a resilient strip 16 normally flat, and retained by eyelets 17, or other suitable means.

On the opposite side of element 10 is a 50 rectangular portion 18 having its outer edge 19 folded over, this portion 18 having score lines 20 therein.

The long edges of the main sheet are folded outwardly at 22, 23 and each of these

folds includes an inner reinforcing thickness 24, so that the pockets or sockets for 55 the ends of resilient strip 16 may be of substantial construction.

A commercial type of paper fastener or wire clip 25 is made use of in forming the pockets, and these devices are passed through the folded portions, in alinement with the score lines 20, and are secured on the inner side. The openings 26 of the pockets thus formed are toward each other, on opposite edges of the portion 18 of the envelope.

On the inner side of the element 10, I secure a strip 28 comprising a central portion of the size of member 10 and including end flaps 29, 30, adapted to overlap and come into immediate contact with the papers to be inclosed. The portions 10, 11, 18 and 19, together with folded portion 13, are formed of one piece, and the elements of the pockets (other than the wire fasteners or staples), are part of the same main sheet of paper or tag board. The reinforcing strip 28 and flaps 29, 30, constitute the other sheet of the envelope, in its complete form.

The papers having been inclosed, portions 11 and 18 are folded along those score lines 80 which will permit of closing the file in compact manner, the strip 16 is flexed, and the ends thereof enter two of the oppositely located pockets, at which time pressure on the element 16 is removed, and the file is properly secured, without the use of tape, bands, or other similar means.

What I claim is:

In a filing envelope, a sheet comprising a plurality of folded portions adapted to overlap, a second sheet extending across the sheet first named and having its ends projecting therefrom but adapted to overlap each other and the sheet first named, and means for securing the free edges of the envelope, said means including a resilient strip having projection ends and means forming pockets for receiving the projecting ends, said means comprising folded over portions on opposite edges of the sheet first named, the outer walls of the pockets being reinforced by an additional fold, providing stiffened edge portions for guiding the ends of the resilient strip into the pockets.

In testimony whereof I affix my signature.
JOHN K. CASSEL.
